UNITED STATES PATENT OFFICE.

ONESIME E. MICHAUD, OF ST. LOUIS, MISSOURI.

VALVE-OPERATING MECHANISM FOR INTERNAL-COMBUSTION ENGINES.

1,170,087.

Specification of Letters Patent.

Patented Feb. 1, 1916.

Application filed January 9, 1915. Serial No. 1,275.

To all whom it may concern:

Be it known that I, ONESIME E. MICHAUD, a citizen of the United States, and a resident of the city of St. Louis and State of Missouri, have invented a new and useful Improvement in Valve-Operating Mechanism for Internal-Combustion Engines, of which the following is a specification.

My invention relates to valve operating mechanisms, particularly to valve operating mechanisms for internal combustion engines.

The principal object of my invention is a valve operating mechanism which positively opens and closes the valves, and which will be rapid and reliable in its operation.

Further objects will appear more fully hereinafter.

Generally stated, the invention consists in a valve operating mechanism in which the valve is opened and also closed positively by the direct action of a tappet mechanism operatively connected to the crank shaft of the engine.

The invention further consists in the parts and in the arrangements and combinations of parts more fully set forth hereinafter.

In the accompanying drawings which form part of this specification, and in which like reference characters refer to like parts throughout the several views, Figure 1 is a vertical cross-section through one cylinder of an upright internal combustion engine showing a valve operating mechanism embodying the invention applied thereto, the valve being in its closed position; Fig. 2 is a fragmentary cross-section similar to Fig. 1 showing the parts of the valve operating mechanism in their positions when the valve is open; and Fig. 3 is a fragmentary section through the lower portion of the valve operating rod and actuating mechanism, showing how the parts operate in case the direction of rotation of the engine is reversed.

Referring to the accompanying drawings, a valve operating mechanism embodying the invention is shown applied to an internal combustion engine of ordinary construction. The engine comprises a cylinder 1 and a crank-case 2 secured to said cylinder. Mounted in the crank-case 2 is a crank-shaft 3 which is connected by means of a crank-arm 4 and a connecting rod 5 to a piston 6 operating in the cylinder 1. Mounted in the crank-case 2 at one side of the crank-shaft 3 and parallel to it is a shaft 7 which

has a sprocket wheel 8 secured thereto. Secured to the crank-shaft 3 is a second sprocket-wheel 9 which has half as many teeth as the sprocket-wheel 8, and connecting said sprocket-wheels is a sprocket chain 10. Also mounted in the crank-case 2, directly above the shaft 7 and parallel to it, is a second shaft 11. The lower shaft 7 and the upper shaft 11 have intermeshing gears 12 and 13 respectively secured thereto. The gears 12 and 13 are of the same size and serve to connect the shafts 7 and 11 so that they rotate in opposite directions. The lower shaft 7 has secured thereto a sleeve 14 which has an integral projection 15 constituting a valve opening cam or tappet. Secured to the upper shaft 11 is a second sleeve 16 which has an integral projection 17 constituting a valve closing cam or tappet.

The valve shown is of the puppet type commonly used in internal combustion engines and is provided with a downwardly projecting stem 18. Secured by a pin 19 to the lower end of the valve stem 18 is a sleeve or collar 20 having a downwardly projecting screw-threaded portion. Interposed between the sleeve 20 and the valve casing, is a compression coil spring 21, which operates to hold the valve in its closed position. Slidably mounted in the crank-case 2 is a valve operating rod 22 which has a longitudinal bore or recess 23 extending downwardly therein from its upper end. The upper portion of this bore is larger than the lower end, forming an axial recess which is screw-threaded at the top and is adapted to receive the screw-threaded portion of the sleeve 20 which is secured to the valve stem 18. Extending through the lower end of the bore into the recess 23 is a plunger 24, which has integral therewith at its lower end a circular head 25, larger than the rod 22. Mounted in the recess 23 surrounding the stem of the plunger is a compression coil spring 26, one end of which engages the bottom of said recess, and the other end of which engages a washer 27. The washer 27 is held in place on the plunger 24 by a pin 28. A circumferential rib or collar 29 surrounds the rod 22 a short distance above its lower end.

In assembling the parts associated with the rod 22, the stem of the plunger 24 is pushed upwardly through the bore into the recess 23 in said rod, the spring 26 and the

washer 27 are inserted through the upper end of the bore into the recess and assembled on the stem, and the pin 28 is inserted in its place in the stem through a hole 30 in the rod 22. The sleeve 20 is then screwed into the upper end of the recess 23 to connect the rod 22 and the valve stem 18.

The operation of the valve operating mechanism is as follows: The tappet 15 engages the under face of the head 25 and, as said head is normally held by the spring 26 against the lower end of the rod 22, the rotation of the shaft 7 in the direction of the arrow (Figs. 1 and 2) raises the rod 22 and 10 opens the valve. The outer surface of the tappet 15 is curved in the arc of a circle having the center of the shaft 7 as its center, and this curved surface engages the head 25 and holds the valve open during the up- 15 stroke of the piston 6. At the end of the up stroke of the piston, the tappet 17 engages the upper face of the collar 29 to push the rod 22 downwardly and close the valve. The parts are so proportioned and connect- 20 ed that the valve is alternately opened and closed at the proper times corresponding to the position of the piston in the cylinder of the engine.

It frequently happens that an engine re- 30 coils and rotates the crank shaft for part of a revolution in the direction opposite to the direction of its normal rotation. When this reverse movement of the crank-shaft occurs, the lower shaft 7 will be rotated in a counter-clockwise direction, as shown by the arrow in Fig. 3. Such rotation of the shaft 7 will cause the tappet 15 to engage the head 25 and move it down, thereby tending to move the valve beyond its closed position. 35 In order to relieve the downward pressure on the valve, which would otherwise result in an injury or breaking of some of the parts, the head 25 and the plunger 24 are separable from the rod 22, and they may 40 move downwardly relative to the rod 22 against the tension of the spring 26.

The valve operating mechanism shown and hereinbefore described operates to open and also to close the valve positively. Accordingly, as the movements of the valve are not dependent upon the action of the spring, they can be made with precision as rapidly as is desirable; and thus the valve mechanism can be timed more accurately than 50 heretofore to attain a greater efficiency and an increased speed of the engine. The spring 21, which normally holds the valve closed, can be weaker than in the case where the closing of the valve depends on this 55 spring alone, thus avoiding severe shocks to the valve when it closes. The arrangement of the valve operating shafts 7 and 11 at one side of the valve operating rod 22 enables the rod 22 to be actuated by a direct 60 push of the tappets 15 and 17 as these tap- 65

pets move upwardly and downwardly respectively. By this construction the sliding friction incident to the use of cam surfaces is largely avoided.

I do not wish to be restricted to the particular construction and arrangement of parts shown and hereinbefore described.

What I claim is:

1. A valve operating mechanism for internal combustion engines comprising a valve, a rod for operating said valve, said rod having members constituting shoulders, and tappets mounted adjacent to said rod and rotating in opposite directions, said tappets being arranged to engage said members of 75 said rod alternately to open and close said valve.

2. A valve operating mechanism for internal combustion engines comprising a valve, a rod for operating said valve, said 80 rod having members constituting shoulders, two shafts arranged one above the other at one side of said rod, and a sleeve secured to each shaft and having a projection capable of engaging one of said members of said 85 rod, said shafts being rotated in opposite directions.

3. A valve operating mechanism for internal combustion engines comprising a valve, a rod for operating said valve, said 90 rod having spaced members connected thereto which constitute shoulders, two shafts mounted adjacent to said rod and geared together to rotate in opposite directions, and a cam secured to each shaft and intermittently engaging one of the shoulders 95 of said rod.

4. A valve operating mechanism for internal combustion engines comprising a valve, a rod for operating said valve, said 100 rod having a collar fixed thereto, a member movably mounted on said rod, the movement of said member being limited in one direction, and tappets mounted adjacent to said rod and operated in opposite directions, said 105 tappets engaging said collar and said member alternately to open and close said valve.

5. A valve operating mechanism for internal combustion engines comprising a valve, a rod for operating said valve, said 110 rod having a collar integral therewith, a plunger slidably mounted in said rod and having a head larger than said rod, said head of said plunger normally engaging the end of said rod, a spring holding said plunger in its normal position, and tappets mounted adjacent to said rod and operated in opposite directions, said tappets engaging said collar and said head alternately to open 115 and close said valve.

6. A valve operating mechanism for internal combustion engines comprising a valve, a rod for operating said valve, said 120 rod having a collar integral therewith, a plunger slidably mounted in said rod and 125

- having a head larger than said rod, said head normally engaging the end of said rod, a spring for holding said plunger in its normal position, two shafts mounted one above the other at one side of said rod and geared together to rotate in opposite directions, a sleeve secured to one shaft and having a projection thereon arranged to engage said collar, and a sleeve secured to the other shaft and having a projection thereon arranged to engage the head of said plunger, said sleeves engaging said collar and said head alternately to open and close said valve.
- 5 7. A valve operating mechanism for internal combustion engines comprising a valve, a rod for operating said valve, a member operatively connected to said rod and movable relatively thereto, means for
- limiting the movement of said member relatively to said rod in one direction, and a tappet mechanism operatively connected to the crank-shaft of said engine and arranged to engage said member during the normal direction of rotation of said crank-shaft in said direction in which the movement of said member relatively to said rod is limited, said tappet mechanism upon reversal of direction of rotation of said crank-shaft of the engine engaging and moving said member relatively to said rod without moving said valve.
